ELECTRICAL CONDUCTOR

Original Filed April 2, 1924

FIG. 1

FIG. 2

INVENTOR
ROBERT R. WILLIAMS
BY *J. W. Schmied*
ATTORNEY

UNITED STATES PATENT OFFICE

ROBERT R. WILLIAMS, OF ROSELLE, NEW JERSEY, ASSIGNOR TO WESTERN ELECTRIC COMPANY, INCORPORATED, OF NEW YORK, N. Y., A CORPORATION OF NEW YORK

ELECTRICAL CONDUCTOR

Original application filed April 2, 1924, Serial No. 703,660. Divided and this application filed June 2, 1928, Serial No. 282,473, and in Canada December 18, 1924.

This is a division of my application for patent Serial No. 703,660, filed April 2, 1924, which has issued as Patent No. 1,689,312 on Oct. 30, 1928.

5 This invention relates to electrical conductors and more particularly to the insulated electrical conductors of submarine cables.

It is an object of the invention to improve 10 the insulation of such conductors both electrically and mechanically and to apply the insulating material to the conductor in such a manner as not to deleteriously affect the conductor itself and in the case of a loaded 15 conductor, to apply the insulating material so that the loading material with which the conductor is wrapped will not be subject to injury.

The use of hard rubber or semi-hard rubber 20 as the material for insulating submarine conductors offers important advantages because of its low conductance, low dielectric constant and the fact that it is more rigid than soft rubber and therefore its osmotic 25 swelling by water absorption is very limited. However, if the rubber compound is vulcanized on the conductor it is very difficult to prevent deformation of the insulation during the long vulcanizing process necessary 30 and, furthermore, the extent of the sulphur attack on the conductor is objectionable during the long period of heating. Moreover vulcanization of the rubber compound on 35 the conductor cannot be accomplished so as to give a satisfactory result in the case of a continuously loaded conductor of the type recently developed. In this conductor, a 40 recently discovered alloy is employed for the loading material, such an alloy having a permeability at low magnetizing forces far in excess of that obtained with the best iron wire heretofore employed for continuous loading. However, to obtain the best results with this new alloy when used in a submarine 45 cable, it is necessary to protect it from mechanical strains induced by hydrostatic pressure exerted on it at sea bottom and to protect against such strains it has been found desirable to impregnate the loaded conductor 50 with an insulating compound such as liquid

bitumen that fills all the interstices between adjacent turns of the loading material and between the loading material and the conductor itself and also in the case of a stranded conductor between adjacent strands of the 55 conductor. To this end, it is preferable to employ an impregnating material which is fluid at the temperature encountered in great depths of water. Complete disclosures of the new loading material and its application to 60 submarine cable conductors are found in patents to G. W. Elmen No. 1,586,884 and O. E. Buckley, Nos. 1,586,874 and 1,586,875, all issued on June 1, 1926. It is not satisfactory 65 to vulcanize the rubber compound on a core 65 of this type in which a layer of liquid bitumen is provided under the insulating material since the liquid bitumen mixes with the rubber compound during vulcanization and hardens 70 to such an extent as to render it useless in 70 protecting the loading material from subsequent strains.

To provide an insulated conductor having the desired characteristics, the invention contemplates the use of an insulating compound which is first vulcanized then rendered plastic and extruded in a continuous 75 sheath about the conductor by means of heat and pressure.

In the accompanying drawings, Fig. 1 is 80 a sectional view of an extruding press by means of which the plastic mass of prevulcanized rubber is extruded about the conductor, and Fig. 2 is a view of a continuously loaded conductor made in accordance with 85 the features of this invention.

In practicing this invention, sheets of vulcanized hard rubber are rendered plastic by working them in standard rubber mills, the rolls of which are heated, or in some other 90 equivalent manner. The term "hard rubber" is here used to also include these compositions sometimes referred to as "semi-hard rubber" in which the sulphur component may be as low as 15 per cent. In order that the vulcanized sheets may be more easily rendered sufficiently plastic to permit the material being extruded, it is desirable to include in the rubber compound a thermoplastic material 95 such as a bitumen, preferably of one of the 100

harder varieties. While the composition of the insulating compound will obviously depend largely upon the temperatures and pressures employed a compound, which may be extruded at a temperature of 150° C. or somewhat less and with extruding pressures of from 1000 to 2000 pounds per square inch consists of approximately 60% rubber, 20% sulphur and 20% bitumen vulcanized at temperatures corresponding to 90 to 100 pounds steam pressure until the free sulphur content is reduced to .5 per cent or less in a manner such as is now commonly employed in the hard rubber industry. In place of or in addition to adding a bitumen to render the vulcanized compound more thermoplastic, it is possible to use, in whole or in part, the material made in accordance with the process described in Patent No. 1,638,535 to Archie R. Kemp, issued on August 9, 1927.

After the vulcanized sheets have been thoroughly worked by the heated rolls of the mill, the plastic mass 3 is fed into the hopper 4 of the extruding press shown in Fig. 1 of the drawings. This press is provided with a tubular central portion 5 into which the extruding material passes as it leaves the hopper, being forced along by means of a rotating worm 6 driven by gear 7. The gear and worm are provided with a hollow central portion through which the conductor to be insulated is driven at a predetermined rate by means not shown. As the conductor emerges through the end of the worm 6, it passes through the compressed plastic mass and the die 9 held in position by a retaining plate 10 maintains the desired outer diameter of the insulated conductor. In order to maintain the insulating material in a plastic condition until after it is extruded, the press is provided with jackets 11, 11 through which live steam is passed from pipes 12, 12. A steam pressure is preferably maintained so as to insure a suitable temperature of approximately 150° C.

In Fig. 2 there is shown the finished conductor comprising a central conducting core 15 surrounded by conductor strands 16, 16 about which is helically wrapped the loading material 17 over which is placed a coating of liquid bitumen 18. The conductor completed thus far is passed through the extruding press where it is provided with a sheath 19 of pre-vulcanized insulating compound.

What is claimed is:

1. In combination, an electrical conductor and a continuous sheath of insulation mainly comprising thermoplastic vulcanized rubber surrounding said conductor.
2. An insulated electrical conductor comprising a conductor having a heavy layer of insulation forming a continuous sheath tightly enclosing said conductor and said insulation comprising thermoplastic vulcanized rubber and hard bitumen, the rubber predominating.

3. A continuously loaded cable comprising a conductor having applied thereabout a magnetic material in the form of an elongated strand and filled with a semi-fluid insulating material and a heavy sheath of thermoplastic vulcanized rubber closely surrounding the filled loaded conductor.

4. An electrical conductor, a magnetic material surrounding said conductor, a continuous sheath of vulcanized rubber around said magnetic material and a filling of pressure equalizing material of at least semi-liquid insulating material within said sheath.

5. A continuously loaded submarine cable comprising a conductor, a magnetic loading material forming a layer loosely surrounding said conductor, a filling of semi-fluid bitumen adjacent to and filling the interstices under said layer of loading material, a heavy sheath of thermoplastic vulcanized rubber surrounding the filled loaded conductor, said sheath forming a seamless envelope in intimate contact with the bitumen.

6. A continuously loaded cable in accordance with claim 5 in which said thermoplastic rubber contains about 20% of hard bitumen.

7. A submarine cable comprising a conductor, a continuous layer of magnetic loading material surrounding said conductor, a continuous seamless sheath enveloping the loaded conductor, said sheath being of rubber vulcanized to a hardness sufficient to prevent a breakdown of its insulating properties during a prolonged submergence in salt water under sea bottom conditions, and a filling within said sheath of a material which remains semi-fluid when the cable is subjected to sea bottom temperatures.

8. A submarine cable comprising a conductor, a continuous layer around said conductor of magnetic material having a desirable magnetic property which is deleteriously affected by strains in the material, a seamless insulating sheath of vulcanized rubber of sufficient hardness to prevent osmotic swelling in sea water, said sheath being jointless over a length of an ordinary section of manufacture and surrounding said layer of loading material, and a filling within said sheath of a pressure equalizing material which during a prolonged exposure of the cable to sea bottom temperatures and pressures, remains sufficiently fluid for a period of years to prevent strains being set up in said magnetic material.

In witness whereof, I hereunto subscribe my name this 31st day of May, 1928.

ROBERT R. WILLIAMS.
